(57) **CLAIM**

The ornamental design for a golf putter grip as shown and described.

DESCRIPTION

FIG. 1 is a first perspective view of a golf putter grip embodying the new design in accordance with a first embodiment;

FIG. 2 is a top view thereof;

FIG. 3 is a bottom view thereof;

FIG. 4 is a front view thereof;

FIG. 5 is a rear view thereof;

FIG. 6 is a left side view thereof, the right side view being a mirror image thereof;

FIG. 7 is a first perspective view of a golf putter grip embodying the new design in accordance with a second embodiment;

FIG. 8 is a top view thereof;

FIG. 9 is a bottom view thereof;

FIG. 10 is a front view thereof;

FIG. 11 is a rear view thereof; and,

FIG. 12 is a left side view thereof, the right side view being a mirror image thereof.

Broken lines in FIGS. 1-12 are included for the purpose of illustrating portions of the golf putter grip which form no part of the claimed design.

1 Claim, 4 Drawing Sheets
